US00D599486S

(12) **United States Design Patent**
Stewart

(10) **Patent No.:** **US D599,486 S**
(45) **Date of Patent:** **** Sep. 1, 2009**

(54) **CURVED MASSAGER WITH PROTRUSIONS**

(75) Inventor: **Thomas E. Stewart**, Laguna Hills, CA
(US)

(73) Assignee: **Sportsheets International, Inc.**,
Huntington Beach, CA (US)

(**) Term: **14 Years**

(21) Appl. No.: **29/321,191**

(22) Filed: **Jul. 11, 2008**

(51) LOC (9) Cl. **28-03**

(52) U.S. Cl. **D24/214**

(58) **Field of Classification Search** D24/200,
D24/211, 214, 215; 601/48, 46, 84, 60, 134-138;
600/38, 39

(57) **CLAIM**

The ornamental design for a curved massager with protrusions, as shown and described.

DESCRIPTION

FIG. 1 is a perspective view of a curved massager with protrusions in accordance with the present invention;

FIG. 2 is a top view of the curved massager with protrusions shown in FIG. 1;

FIG. 3 is a bottom view of the curved massager with protrusions shown in FIG. 1;

FIG. 4 is rear view of the curved massager with protrusions shown in FIG. 1;

FIG. 5 is front view of the curved massager with protrusions shown in FIG. 1;

FIG. 6 is a right side view of the curved massager with protrusions shown in FIG. 1; and,

FIG. 7 is a left side view of the curved massager with protrusions shown in FIG. 1.
